UNITED STATES PATENT OFFICE

EFFINGHAM P. HUMPHREY, OF DRIFTON, PENNSYLVANIA

GYROSEPARATOR

Application filed February 24, 1931. Serial No. 517,933.

My invention relates to an apparatus for hydraulically separating or classifying mixtures of materials of different specific gravities, such as coal and slate, ore and gangue.

5 An object of the invention is to classify or separate the various materials mentioned, with the employment of a minimum amount of liquid.

A further object is to provide an apparatus which may be readily adapted to operate most efficiently upon different grades and kinds of material.

Other objects and advantages not specifically mentioned will become apparent during the course of the following detailed description when read in conjunction with the accompanying drawings which form a part of this specification and in which:

Figure 1 is a vertical sectional view of an apparatus embodying my invention;

Fig. 2 is a top plan view thereof and

Fig. 3 is a horizontal sectional view taken on the line 3—3 of Fig. 1.

Referring now to the drawings in detail, 25 wherein like numerals refer to like parts throughout the same, 5 indicates a liquid tank of any desired shape or capacity from which liquid is delivered under pressure to a circular classifying tank 6. The liquid is drawn from the tank 5 through the intake conduit 7 of a motor driven centrifugal pump 8. The pump 8 is shown as being driven from an electric motor 9 through a shaft 10 although any other available source 30 of power may be used.

The liquid is delivered from the pump 8 through a feed pipe 11 into a drum shaped header 12 carried on the bottom wall 13 of the tank 6. The header 12 is provided with 40 a plurality of radially extending conduits 14 which extend horizontally from the side of the head 12. The conduits may be of varying length and number to suit different conditions in the operation of the device and each terminates in a circumferentially directed discharge nozzle or jet 15. The nozzles 15 are all directed in the same circumferential direction so as to set up a whirling or rotary motion of the liquid mass in 45 the tank 6.

The mixture of material to be classified is fed from a feed chute 16 into an upright tubular feed well 17 from the lower end of which it is discharged onto a distributing cone 18, the apex of which is centrally located with respect to the lower end of the well 17. As the material is evenly distributed into the liquid current from the circular edge 19 of the cone 18 it is efficiently divided, the lighter portions being carried around and upwardly and the heavier sludge material being precipitated to the bottom 13 from which it is discharged through bottom refuse discharge valves 20 or side discharge valves 21.

As the material of less specific gravity is carried upwardly by the liquid current, it is discharged over the top edge 22 of the tank 6 onto an annular overflow launder or spout 23. The launder is disposed at an angle so as to discharge the overflow from the spout 24 thereof onto a dewatering shaker screen 25. The screen 25 is provided with the proper sized mesh to separate the cleaned material from the overflowing liquid mixture and is suitably supported preferably above the tank 5 by appropriate upright members 26.

The mixture of fluid and material which passes through the shaking screen 25 is caught by a funnel shaped hopper 27 and 80 discharged through the spout 28 into the tank 5. It will be noted that the shaking screen 25 is inclined from the spout 24 toward a suitable delivery chute 29 upon which the washed product is delivered from the 85 shaking screen.

The sludge or other heavy matter discharged from the valves 20 is deposited upon an inclined refuse chute 30, a splash guard 31 being provided for the valve discharging onto the lower part of the chute.

It will be understood that depending on the material to be operated upon, the number, size and angularity of the nozzles 15 may be varied as desired. Also the size of the cone 18, the edge 19 of which determines the opening through which the agitating liquid must flow in passing upwardly from the nozzles 15, may be varied to regulate the velocity of liquid passing through the opening be-

tween said edge and the sides of the tank 6. The results of the separation may also be controlled through regulation of the speed of the motor 9 or throttling of the pump 8.

In the operation of the device and in carrying out my process, the tank 5 being filled with water or other suitable liquid, the pump 8 is placed in operation to draw the water from the tank and discharge the same through the pipe 11 into the header 12 from whence it is discharged under pressure through the nozzles 15. When the classifying tank 6 fills to overflowing, the material to be operated upon is fed into the well 17. Under the action of the pressure discharge from the nozzles 15, the water in the tank assumes a whirling or rotary motion, the current passing upwardly in a spiral path. The material falls from the well 17 onto the cone 18 and as it rides off of the distributing edge 19 thereof is caught up by the rising current, the material of less specific gravity being whirled to the top and over the edge 22 of the tank. The sludge and heavy matter falling to the bottom will be slowly swept around due to the rotary motion of the fluid mass and may be readily removed through the discharge valves.

As the overflow from the tank 6 carrying the separated material is discharged by the launder 23 onto the shaking screen 25, another separation takes place, the water and smaller particles being discharged back to the tank 5 while the wanted washed product is delivered to a point of deposit.

While a preferred embodiment of the invention has been shown and described, it will be understood that various changes in the details of construction may be made without departing from the spirit of the invention as defined by the appended claims.

I claim:

1. A hydraulic classifying apparatus including a classifying tank, a distributing cone centrally disposed in said tank, means for feeding material to be classified onto said cone, a header centrally supported in the lower portion of said tank, a plurality of radially extending conduits carried by said header, each of said conduits having a circumferentially disposed liquid discharging nozzle, certain of said nozzles being positioned in the line of travel of material discharged from said cone, and means for introducing liquid under pressure into said header.

2. A hydraulic classifying apparatus including a classifying tank, a header supported in the lower portion of said tank, a distributing cone carried by said header and centrally disposed within said tank, means for feeding material to be classified onto said cone, a plurality of radially extended conduits carried by said header, each of said conduits having a circumferentially disposed liquid discharging nozzle, certain of said nozzles being positioned in the line of travel of material discharged from said cone, certain other of the said nozzles being positioned out of line of travel of material discharged from said cone, and means for introducing liquid under pressure into said header.

3. A hydraulic classifying apparatus including a classifying tank, a header supported in the lower portion of said tank, a distributing cone carried by said header and centrally disposed within said tank, means for feeding material to be classified onto said cone, a plurality of radially extended conduits carried by said header, each of said conduits having a circumferentially disposed liquid discharging nozzle, certain of said nozzles being positioned in the line of travel of material discharged from said cone, certain other of the said nozzles being positioned within the circumference of said distributing cone, and means for introducing liquid under pressure into said header.
